UNITED STATES PATENT OFFICE.

CHARLES H. FOSTER, OF ELIZABETH, NEW JERSEY, ASSIGNOR TO THE
SINGER MANUFACTURING COMPANY, OF NEW JERSEY.

HEMSTITCH SEWING-MACHINE.

SPECIFICATION forming part of Letters Patent No. 634,208, dated October 3, 1899.

Application filed September 22, 1898. Serial No. 691,669. (No model.)

To all whom it may concern:

Be it known that I, CHARLES H. FOSTER, a citizen of the United States, residing at Elizabeth, in the county of Union and State of New Jersey, have invented certain new and useful Improvements in Hemstitching Sewing-Machines, of which the following is a specification, reference being had therein to the accompanying drawings.

- 10 This invention relates to a machine for doing that class of hemstitch-work known as "spoke-stitching" and in which two lines of stitches are formed, one at each side of the row of openings forming the hemstitch-work, the object of the invention being to provide a strong and durable machine for doing the class of work referred to which is simple in construction and which is adapted for rapid operation.
- 20 In the accompanying drawings, Figure 1 is a side view, partly in vertical section, of the improved machine; and Fig. 1^a is a detail view of a part of the operating mechanism of the thread-dividing spur. Fig. 2 is a bottom view of the machine. Fig. 3 is a detail plan or top view of the cam for operating the thread-dividing spur. Fig. 4 is a front end view of the machine, partly in section and with the face-plate removed. Figs. 5 and 6 are detail views 30 from opposite sides of the needle-carriers and connected parts, the thread-dividing spur also being shown. Fig. 7 shows the block or cross-head attached to the lower end of the needle-bar and in which the needle-carriers are pivotally mounted. Fig. 8 is a detail view of the needle-carriers removed from said block. Fig. 9 is an enlarged cross-section of the thread-dividing spur and needles with the latter closed against said spur, and Fig. 40 10 is a detail plan view of the thread-dividing spur and the arm on which it is formed.
- A denotes the work-plate, and B the bracket-arm, of a sewing-machine which in its general construction is that of one of the well-known styles of Singer machines and which need not, therefore, be very particularly described.
- C is the driving-shaft, journaled in the upper part of the arm B and having, as usual, 45 at its forward end a crank connected by a pitman d to the needle-bar D. The shaft C is
- provided near its rear end with a bevel-gear e, meshing with a similar bevel-gear e at the upper end of a vertical shaft E, journaled in the vertical portion of the arm B and carrying at its lower end a crank-disk e¹², connected by a pitman e¹ to an arm e² of a rock-shaft e³, having a second arm e⁴ engaging a crank-arm e⁵ on the shuttle-operating rock-shaft e⁶, carrying the shuttle-driver e⁷ to operate the oscillating shuttles e⁸. This shuttle-operating mechanism is that of the well-known Singer overseaming-machine, excepting that in the present instance two closely-placed shuttles are employed instead of one, as heretofore, in 55 this style of machine.
- The shaft E is provided beneath the work-plate with a gear-wheel e⁹, meshing with a larger gear-wheel F, journaled on the stud F', and which performs one rotation to three rotations of the shaft E and of the driving-shaft C, said gear-wheel F being provided with a cam-groove f', entered by a pin or roller-stud f², carried by one arm of a bell-crank lever f³, the other arm of which engages the feed-lever f⁴, pivoted on an adjustable fulcrum f⁵, with which the feed-regulating bar f⁶ is provided, the feed-dog f⁷ being attached to or connected with the forward end of said feed-lever in the usual or any well-known manner. 60
- The crank-disk e¹² is provided in its upper face with a cam-groove g, entered by a pin or roller-stud carried by one arm of a bell-crank lever G, to the other arm of which is jointed the rear end of a pitman g', connected 65 at its forward end to a lever g², pivoted in a projection or bracket g³ on the shuttle-race g⁴. The forward end of the lever g² extends beneath a vertically-reciprocating rod g⁵, having an arm or offset portion g⁶ at its upper end, and which arm or offset portion is provided with the thread-dividing prong or spur g⁷. The rod g⁵ is preferably forced downward by a coil-spring g⁸, interposed between a portion of the shuttle-race (in which the bearing for said rod is formed) and the milled head g⁹ of a screw tapped in the lower end of said rod. A slight adjustment between the rod g⁵ and its operating-lever g² is preferably provided by means of the screw g¹², against 70 a head on the upper end of which the abutting milled head g⁹ rests. This adjustment 75
- 80
- 85

- 95
- 100

permits of a slight variation vertically of the spur g^7 to bring it into proper operating position relative to the other parts or to compensate for any slight differences of construction should such occur in different machines.

5 The arm or offset part g^6 of the rod g^5 is formed as a thin blade and is arranged between the two shuttles, so that said arm and the spur g^7 serve partly as a thread-separator between the two needles and shuttles, the small depending fin or rib m on the plate m' also serving partly as a thread-separator. The spur g^7 is recessed for the reception of the needles when the latter are closed together, as shown more clearly in Fig. 9. Fig. 1 represents the arm or part g^6 with its spur in front of one of the shuttles e^8 , the other shuttle (which would occupy a position in front of or toward the observer from said arm 20 g^6) being removed.

The shaft C is provided with a bevel-gear c' , meshing with a larger bevel-gear, with which the cam-disk II is provided, these gears being so proportioned that the said cam-disk 25 makes one revolution to each three revolutions of the driving-shaft. The cam-groove h of the disk II is entered by a pin or roller-stud at or near the upper end of a lever h^2 , pivoted at h^3 to the bracket-arm B, said lever 30 being provided with a groove which receives an adjustable slide at the rear end of the pitman h^4 , said slide being secured in any desired position of adjustment in the usual manner by the thumb-nut h^5 . The pitman 35 h^4 is connected at its forward end to a lug or projection i on a swinging frame I, pivoted in the head b of the bracket-arm on the center screws b' . The swinging frame I is provided with a vertical rod i^2 , on which is fitted 40 a slide i^3 , having a stud entering a head i^4 of an arm i^5 , attached by a screw i^6 to the pivoted needle-carrier d^2 , said needle-carrier having a notch or slot entered by a tooth or projection d' , with which a second pivoted needle-carrier d^3 is provided. The needle-carriers (to 45 which the needles d^4 are secured by set-screws d^5) are formed with pivot-studs entering bearings d^6 in a block or cross-head d^7 , attached to the lower end of the needle-bar D, said 50 carriers being secured in their bearings in said block or cross-head by screws d^8 . The tooth or projection d' is preferably formed on a small plate d^9 , adjustably secured to the needle-carrier d^3 , so that by a slight change 55 of position of said tooth, when necessary, the vibrating positions of the needles may be equalized, so that they will both have the same degree of inclination when their points are closed against the thread-dividing spur g^7 .

60 Attached to the block or cross-head d^7 by a screw k is a small bracket or plate k' , provided at its lower end with a socket for the reception of an awl or pricker k^2 , having a bent or offset shank portion, the said awl or pricker being held in its socket by the set-screw k^3 . The lower or working portion of 65 the said awl or pricker is arranged in front

(in the line of the feed of the work) of the thread-dividing prong or spur g^7 a distance just equal to the length of the movement of the work by the feed. If the length of the feed be varied, the position of the working portion of the awl or pricker can be varied to correspond by loosening the set-screw k^3 slightly and turning the said awl or pricker in its socket, the cranked or offset portion of the shank of the said awl or pricker permitting the working portion thereof to be swung toward and from the vertical plane of reciprocation of the thread-dividing spur without appreciably disturbing the alinement of the said working portion of the said awl or pricker with said spur. The awl or pricker k^2 serves, as will be understood, as an initial thread-divider to form holes in the fabrics, and which holes will be entered and enlarged after the next feeding movement of the work by the thread-dividing spur g^7 previous to the entrance of the needles. This awl or pricker k^2 , although a desirable feature of the improved machine, is not indispensable in the successful operation thereof and might therefore be omitted without departing from the essence of the invention.

From the connection of the needle-carriers 95 d^2 d^3 with the grooved cam h , as hereinbefore described, it will be apparent that said needle-carriers will be vibrated (through the lever h^2 , pitman h^4 , swinging frame I, and arm i^5 , which arm is connected through the slide i^3 to the rod i^2 , carried by said swinging frame) to move the needles from and toward each other to the separated and closed positions shown by full and dotted lines, respectively, in Figs. 5 and 6. As the cam-disk H 100 performs one revolution to each three revolutions of the driving-shaft, and consequently to each three vertical reciprocations of the needles and each three oscillations of the shuttles, the needle-carriers will be vibrated once to every three stitches formed by each needle and shuttle. The grooved cam h is so formed that the needles will be in their separated positions in making one stitch and in their closed positions when making two 105 stitches. Owing to the geared connection hereinbefore described of the feed cam-wheel F with the driving-shaft, it will be understood that the feed-dog will in the present machine be operated to feed the work once for each 110 three stitches or once for each three vertical reciprocations of the needle-bar, and this feeding movement is in this machine timed to occur between the two reciprocations of the needle-bar performed when the needles 115 are in their closed positions. A differently-timed feed might, however, be employed—as, for example, an ordinary hemstitch-feed, which moves the work forward twice and backward once, and thus a different spoke-stitch seam might be formed without otherwise changing the machine.

The thread-dividing spur, which is arranged adjacent to the vertical paths of the needles

when the latter are in their closed positions, performs one reciprocation at each vertical reciprocation of the needles and is so timed as to rise through the work as the needles are descending, so that its point will be above the work before the points of the needles enter the latter, and thus when the needles are in their closed positions they will be partly housed in, and thus guided by the recesses or 5 grooves formed in the opposite sides of said spur for their reception, the said spur descending before the needles rise, so as to leave the hole in the fabric free for the drawing of the needle-threads when the shuttles 10 are expanding the needle-loops and so that said spur will be disengaged from the work when the latter is fed.

When the thread-dividing spur rises, it passes upward in the hole which has been 20 preferably previously made by the awl or pricker k^2 , the hole being enlarged and the divided threads being held apart by the said spur and by the needles while the stitches are being formed, the threads of the stitches 25 which pass through the holes in the work or between the divided threads of the fabrics being anchored into the body of the fabrics when the needles descend in their separated positions.

30 The work performed by the improved machine is similar to that made in the machine shown in United States patent to Gegauf, No. 592,088, dated October 19, 1897, as illustrated in Figs. 5 and 6 of the drawings of said patent. In the use of the Gegauf machine, however, only straight or approximately straight hemstitch or spoke-stitch seams can be made, owing to the fact that the needles are arranged one behind the other in the line of the 35 feed of the work, and consequently as sharp corners cannot be turned—as is necessary, for example, in hemstitching handkerchiefs, square tidies, &c.—as can be done with the improved machine herein described. It has 40 been found, moreover, that by arranging the thread-dividing spur beneath the throat-plate or work-plate a more convenient and more reliably operating mechanism is provided in that said spur does not interfere 45 with the needles to prevent the proper running of the needle-threads as the latter are drawn down by the shuttles, and said spur also serves to guide the needles as they descend, and by constructing the machine with 50 a simple and positively-operating needle-vibrating mechanism higher speed and more durability are attained than with the Gegauf construction. The invention, therefore, is not to be understood as being limited to the 55 details herein shown and described, as these may be varied widely without departing from the spirit of the invention.

Having thus described my invention, I claim and desire to secure by Letters Patent—

60 1. In a sewing-machine the combination with a needle-bar and its operating mechanism, of two needle-carriers movably connected

with said bar and provided with needles, mechanism for operating said carriers to move the said needles from and toward each other, 70 loop-taking devices coöperating with said needles, a thread-dividing spur arranged beneath the work-plate of the machine and adjacent to the paths of descent of said needles, means for operating said spur to cause it to 75 rise through the work before the descending needles enter the latter, an awl or pricker arranged above the work-plate in front of said spur in the line of feed of the work, and a work-feeding mechanism.

80

2. In a sewing-machine the combination with a needle-bar and its operating mechanism, of two needle-carriers movably connected with said bar and provided with needles, mechanism for operating said carriers to move 85 the said needles from and toward each other, loop-taking devices coöperating with said needles, a thread-dividing spur arranged beneath the work-plate of the machine and adjacent to the paths of descent of said needles, 90 means for operating said spur to cause it to rise through the work before the descending needles enter the latter, an awl or pricker arranged above the work-plate in front of said spur in the line of feed of the work, and a 95 work-feeding mechanism timed to move the work forward once for each three vertical reciprocations of said needle-bar.

3. In a sewing-machine the combination with a needle-bar and its operating mechanism, of two needle-carriers movably connected with said bar and provided with needles, mechanism for operating said carriers to move the said needles from and toward each other, 100 loop-taking devices coöperating with said needles, a thread-dividing spur arranged beneath the work-plate of the machine and adjacent to the paths of descent of said needles, 105 means for operating said spur to cause it to rise through the work before the descending needles enter the latter, an awl or pricker arranged above the work-plate in front of said spur in the line of feed of the work, and a work-feeding mechanism timed to move the 110 work forward once for each three vertical reciprocations of said needle-bar, said operating mechanism for said needle-carriers being 115 timed to cause the needles to be separated at one descent of the needle-bar and to be closed together at the next two descents thereof, the 120 closed descents of the needles occurring just before and just after the feeding movement.

4. In a sewing-machine the combination with the driving-shaft thereof and a needle-bar operatively connected with said shaft, of 125 two pivoted and connected needle-carriers reciprocating vertically with said bar and one of which carriers is provided with an operating-arm, as v , needles mounted in said carriers, a cam-disk, as H , geared to said shaft 130 to rotate one to each three revolutions of the latter, connections between said arm and cam whereby said arm is vibrated to move the said needles toward and from each other, a thread-

dividing spur arranged beneath the throat-plate of the machine, mechanism for reciprocating said spur vertically, and a feeding mechanism for advancing the work.

- 5 5. In a sewing-machine the combination with a needle-bar and its operating mechanism, of two pivoted needle-carriers reciprocating vertically with said bar and having a toothed connection with each other so as to 10 be reversibly vibrated, one of said carriers being provided with an operating-arm, needles mounted in said carriers, means for vibrating said arm to move the said needles from and toward each other, a thread-dividing spur located beneath the work-plate or 15 throat-plate and adjacent to the paths of descent of said needles, mechanism for reciprocating said spur vertically to cause it to rise through the goods before the needles enter 20 the latter, and a feeding mechanism for advancing the work.
6. In a sewing-machine, the combination with the driving-shaft and the needle-bar operatively connected therewith, of two pivoted 25 needle-carriers having a toothed connection with each other and one of which is provided with an operating-arm, as i^5 , needles mounted in said carriers, and a cam geared to said shaft and operatively connected with said 30 arm so as to move the said needles toward and from each other at intervals.
7. In a sewing-machine, the combination with the driving-shaft thereof and a needle-bar operatively connected with said shaft, of 35 a cam, as H, geared to said shaft, two pivoted needle-carriers reciprocating vertically with said bar and having a toothed connection with

each other, one of said carriers being provided with an operating-arm as i^5 , a movable frame as I, to which said arm is connected 40 and which, in turn, is with said cam, to be operated thereby, needles mounted in said carriers, loop-taking devices coöperating with said needles, a work-feeding mechanism, a thread - dividing spur located beneath the 45 work-plate or throat-plate of the machine adjacent to the path of descent of said needles, and means for reciprocating said spur vertically to cause it to rise through the work before the needles enter the latter. 50

8. In a sewing-machine, the combination with two needles and means for reciprocating the same vertically and for moving them toward and from each other, and loop-taking devices coöperating with said needles, of a 55 thread - dividing spur located beneath the work-plate or throat-plate of the machine adjacent to the paths of descent of said needles, operating mechanism for reciprocating said spur vertically, a feeding mechanism for advancing the work, and a vertically-reciprocating awl or pricker above the work-plate located in front of said spur and in the line of the feed, said awl or pricker being adjustable so that the distance of its working portion from the vertical path of movement of said spur may be varied to correspond to different lengths of feed. 60

In testimony whereof I affix my signature in the presence of two witnesses.
